CLAIM

The ornamental design for a lion origami car, as shown and described.

DESCRIPTION

FIG. 1 is a perspective view of the lion origami car.

FIG. 2 is a first top plan view thereof with table unit retracted.

FIG. 3 is a first side elevational view thereof.

FIG. 4 is a front elevational view thereof.

FIG. 5 is a rear elevational view thereof.

FIG. 6 is a second side elevational view thereof; and,

FIG. 7 is a second top plan view thereof showing table unit extended.

The broken lines represent portions of the article that form no part of the claim.
